FIGURE 1 is a front view of a condition control device embodying the new design;

FIGURE 2 is a side view as seen from the right side of the device, the left side being substantially a mirror image thereof;

FIGURE 3 is a top view of the device;

FIGURE 4 is a fragmentary cross-sectional view taken generally along line 4—4 of FIGURE 1; and

FIGURE 5 is a front perspective view of the device.

The back and bottom of the device are essentially plain.

The dominant features of the design reside in the portions shown in full lines.

I claim:

The ornamental design for a condition control device, substantially as shown and described.
